PROCESS OF FORMING TUBES AND APPARATUS THEREFOR.

1,088,650.

Specification of Letters Patent.

Patented Feb. 24, 1914.

Application filed August 29, 1913. Serial No. 787,245.

To all whom it may concern:

Be it known that I, LOUIS H. BRINKMAN, a citizen of the United States, and a resident of Glen Ridge, in the county of Essex and State of New Jersey, have invented a certain new and useful Improvement in Processes of Forming Tubes and Apparatus Therefor, of which the following is a specification.

My invention relates to a process of forming tubes by cross-rolling billets or other cylindrical bodies and apparatus therefor.

The object of the invention is to provide a process and apparatus for carrying out the same whereby tubes may be rapidly and economically made from billets or other cylindrical bodies of larger inner diameter than the desired tube, and the invention consists in the process and apparatus herein-after described for attaining these results.

In carrying out my process, I subject the metal of the billet or cylindrical body, to what is known as "cross-rolling", to extend or elongate the metal. The construction, arrangement and use of rolls or disks for cross-rolling hot billets to pierce them for the purpose of subsequently forming tubes by the draw-bench method, and the further carrying out of the cross-rolling principle to form tubes from hot billets by the provision of a plurality of sets of rolls or disks suitably arranged to act on the metal at successive points along "the pass" so as to progressively and simultaneously reduce the thickness of the billet and elongate the metal at these points, are matters well understood in the art, so that in describing my invention, I will only briefly refer to the arrangement of the cross-rolling devices in so far as concerns this much of their function in the present invention.

Broadly stated, my improved process of forming tubes by cross-rolling billets, or other cylindrical bodies, comprises simultaneously and progressively reducing the thickness of the metal and the inner diameter of the body at successive points along the pass by continuously and simultaneously subjecting the metal at these points to cross-rolling action so as to press it inwardly and extend it longitudinally.

In the preferred embodiment of practising my process, I subject the metal to cross-rolling action continuously and simultaneously at successive points along the pass, by separate sets of cross-rolling bodies at these

points which act upon the metal at these points with progressively increasing ratio of feeding to cross-rolling components, while supporting the billet upon a stepped-down mandrel having shoulders at these successive points which serve to back up the metal under the cross-rolling bodies so as to localize the crushing or pressure component of the cross-rolling bodies to the short portion of the metal extending beyond the successive shoulders and not yet engaged and bent down by the cross-rolling bodies, so that the metal as it is fed beyond the shoulders while rotating, is engaged by the cross-rolling bodies and permanently bent down over the shoulders to the inner diameter of the next succeeding section of the mandrel, the metal being continuously and progressively spread or extended longitudinally at these successive points along the pass simultaneously with the progressive reduction of its diameter, the cross-rolling bodies tending to draw the cylindrical body along the pass.

The invention will be more fully understood from the following description taken in connection with the accompanying drawing, showing a longitudinal view, mostly in section, of the preferred form of apparatus for carrying out my process.

The hot billet, or cylindrical body, 1 to be rolled is mounted on the support 2 in the form of a stepped mandrel—that is a mandrel consisting of a plurality of sections 3—7, each of less diameter than the preceding one, and having shoulders 8—11 between successive sections. These shoulders are preferably rather abrupt and concave in section, and each is of less height than the preceding one, so that the difference in the diameters of successive sections gradually decreases. At each shoulder or step are provided suitable means, such as rolls or rotatable disks 12—19, suitably arranged to rotatably engage the metal at these points so as to subject it to cross-rolling action. The various forms of rolls or disks and their arrangement with respect to "the pass" and to each other to produce what is generally known as "cross-rolling" is well understood in the art, as is also the relative shapes and peripheral speeds of the rolls or disks at the successive points along "the pass", and their relative angles to the axis of "the pass" to produce cross-rolling action in which the feed or forward thrust component increases

with successive rolls to take care of the elongated metal and to produce tension between the successive pairs of rolls.

In the preferred form of my invention the working or engaging peripheries 20-21 of the first pair of disks 12-13 are of relatively short radius in section as compared with those of the succeeding pairs, the sectional outline of the working surfaces of the successive pairs of disks being of gradually increasing radius until finally the working surfaces 26, 27 of the last pair are comparatively broad and fairly flat so as to serve mostly to smooth out the ridges or grooves, formed in the metal by the preceding rolls, to produce a smooth product.

The cross-rolling action of the disks in this apparatus would tend to thrust the mandrel longitudinally, and in order to prevent this, I provide suitable means to hold the mandrel from longitudinal movement under the cross-rolling action, the said means being so arranged as to permit the billet or cylindrical body to be slipped on the mandrel over its rear end. This means, in its preferred form, consists of a stationary support 28 having an annular part 29 preferably concentric with the mandrel and provided with threads 30 into which is threaded a ring 31 carrying an outer bearing 32 for a series of balls 33, upon which is mounted an inner ring 34 having projections 35 in which are threaded set screws 36 adapted to engage in a groove 37 at the rear end of the mandrel. The inner ring 34 is provided with an annular bearing portion 38 which forces the balls against an annular shoulder 39 of bearing 32 when the cross-rolling action is started. The difference between the diameters of the inner ring 34 and the rear end of the mandrel is such as to permit billets of the desired thickness to be slipped over the rear end of the mandrel in place upon section 3 by simply withdrawing the set screws 36.

The operation of the apparatus described is as follows: When it is desired to place the billet upon the mandrel the screws 36 are removed and the billet slipped over the rear end of the mandrel. The disks or rolls are then started up and the hot billet pushed in place against the first pair of rolls which engage the billet and by their cross-rolling action force the metal down upon the shoulder 8 extending the metal longitudinally, thereby simultaneously elongating the metal and decreasing the inner diameter of the billet at this point. These rolls continuously operate upon the billet to elongate the metal at this point, and as the elongated metal reaches the second pair of rolls 14-15 they take hold of the metal and by cross-rolling action force the metal down upon the shoulder 9 to again reduce the thickness of the metal and its inner diameter, while the first

pair of rolls are simultaneously operating, and so on through as many rolls as it may be desired to use, until the last pair of rolls are reached. The step or shoulder 11 under these rolls is comparatively low and the surface of the rolls being broad and flat acts mainly to press out the ridges or irregularities in the surface of the metal to produce a smooth product.

Having thus described my invention, what I claim as new and desire to secure by Letters Patent, is:

1. The process of forming a metal tube from a cylindrical body of larger diameter, which comprises simultaneously and progressively at successive points along the length of the body, spreading the metal longitudinally and forcing it inwardly permanently to reduce the inner diameter of the body, by subjecting it to continuous and simultaneous cross-rolling action at said successive points and rolling the metal down at said points against shoulders of a stepped-down mandrel.

2. The process of forming a metal tube from a cylindrical body of larger diameter, which comprises simultaneously and progressively at successive points along the length of the body, spreading the metal longitudinally and forcing it inwardly permanently to reduce the inner diameter of the body, by subjecting it to continuous and simultaneous cross-rolling action at said successive points by separate sets of cross-rolling bodies which act to roll the metal down at said points upon inner supporting shoulders of progressively reduced diameters.

3. The process of forming a metal tube from a cylindrical body of larger diameter, which comprises simultaneously and progressively at successive points along the length of the body, spreading the metal longitudinally and forcing it inwardly permanently to reduce the inner diameter of the body, and producing tension in the metal between said points, by subjecting it to continuous and simultaneous cross-rolling action at said successive points by separate sets of cross-rolling bodies having their working faces convex longitudinally of the pass and acting upon the metal with progressively increasing ratios of feeding to cross-rolling components to roll the metal down at said points upon successive shoulders of an inner supporting stepped-down mandrel.

4. In a machine for forming a metal tube from a cylindrical body of larger diameter, the combination of an inner support for the body having successive annular shoulders formed thereon of progressively reduced diameter toward the finishing end of the machine, and separate sets of cross-rolling bodies at the successive shoulders operatively related thereto for simultaneously cross-rolling the cylindrical body thereat to continu-

ously and simultaneously force the metal down upon the successive shoulders so as to simultaneously and progressively reduce the thickness of the metal, elongate it, and reduce the inner diameter of the cylindrical body at said points.

5. In a machine for forming a metal tube from a cylindrical body of larger diameter, the combination of means for supporting the 10 cylindrical body comprising a mandrel stepped down toward the finishing end of the machine to provide a series of shoulders of progressively reduced diameter, and sets of cross-rolling devices at the successive 15 shoulders, operatively positioned with respect to the "pass" to simultaneously rotatively engage the metal of the cylindrical body to cross-roll it, each succeeding set acting upon the metal with an increased 20 ratio between the feeding and cross-rolling components, to continuously and simultaneously force the metal down upon the successive shoulders so as to simultaneously and progressively extend the metal, produce tension 25 therein between the successive points of cross-rolling and reduce the inner diameter of the cylindrical body at such points.

6. In a machine for forming a metal tube

from a cylindrical body of larger diameter, the combination of an inner support for the 30 body having successive annular shoulders formed thereon of progressively reduced diameter toward the finishing end of the machine, separate sets of cross-rolling bodies at the successive shoulders operatively related 35 thereto for simultaneously cross-rolling the cylindrical body thereto to continuously and simultaneously force the metal down upon the successive shoulders so as to simultaneously 40 and progressively reduce the thickness of the metal, elongate it, and reduce the inner diameter of the cylindrical body, at 45 said points, and means for securing the rear end of the inner support to prevent longitudinal movement thereof under the cross-rolling action, whereby the operative relation of the shoulders and the cross-rolling bodies is maintained.

In testimony whereof, I have signed my name to this specification, in the presence of 50 two subscribing witnesses.

LOUIS H. BRINKMAN.
